PRINTING FURNITURE

Charles Reckeweg, Washington, D. C.

Application September 9, 1935, Serial No. 39,843

7 Claims. (Cl. 101—402)

The present invention relates to printing furniture particularly adapted for use in locking up type arranged in any suitable manner in a chase, for use on cylinder and vertical presses.

5 In the printing industry to-day, the majority of type is set by machine and cast into oblong slugs or type bars. After the casting operation has been completed, the slugs, as they are termed, are automatically trimmed on the edges. During 10 the trimming operation, if the knives become dull or are dull, the edges of the slugs are rough and uneven, then too the edges of the slugs are not always trimmed true, consequently when a number of these slugs are set up in forms, an 15 uneven surface appears. Due to the irregular surfaces or edges, the furniture as used to-day in the trade will not hold the type on its feet when locked up in the chase. Stripping has been resorted to in an endeavor to prevent work-ups 20 which consume a great deal of time of the pressman, and to some extent the stripping assists in holding the type on its feet, but even with the stripping there is the uncertainty of registering. Stripping the form as applied to the trade is the 25 placing of a narrow strip of paper or cardboard about a quarter of an inch high around the form and between the present day furniture.

Actual experiments conducted by me in the 30 trade have proven, that the only possible way that type can be securely held on its feet and work-ups eliminated, as well as eliminating the time required to strip a type form, is the form of furniture herewith illustrated, described and 35 claimed.

One of the primary objects of my invention is the provision of novel printing furniture that will impinge type forms at their lowermost portions, thereby keeping the type on its feet.

40 Another object of my invention is the provision of novel printing furniture that when locked in a chase with type forms, will securely hold the type on its feet, and on the bed of the press.

A further object of my invention is the provision 45 of novel printing furniture that eliminates work-ups.

A still further object of my invention is the provision of novel printing furniture that eliminates stripping the forms.

50 A still further object of my invention is the provision of novel printing furniture that assists in eliminating slurring and wrinkling during the printing operation.

A still further object of my invention is the 55 provision of novel printing furniture that assists

in disposing of air trapped between the paper being printed and the type form.

A still further object of my invention is the provision of novel printing furniture that provides a channel way around the type form when 5 locked in a chase.

With these and other objects in view, the invention consists of novel construction and arrangement as will be hereinafter more specifically described, claimed and illustrated in the 10 accompanying drawing, in which drawing:—

Figure 1 is a perspective view of my novel printing furniture.

Figure 2 is an end elevational view of same.

Figure 3 is a perspective view of a chase, a type 15 form in the chase surrounded by my novel furniture and locked therein.

Figure 4 is a transverse sectional view taken on line 4—4 of Figure 3.

The numeral 5 represents a chase of the type 20 used in the printing trade. Within the inner confines of the chase 5 is a type form 6, which as illustrated in Figure 3 of the drawing is surrounded by pieces of my novel furniture 7. The furniture 7 as illustrated per se in Figures 1 and 25 2 of the drawing may be of any suitable length, width and thickness, and in the present showing I have illustrated the furniture as chase high. The furniture is provided with a rabbet 8 on each longitudinal edge and it is cut to a depth 30 of approximately one-half of the total height of the furniture. If furniture is used thicker than chase high, the portion of the furniture represented by the numeral 10 remains the same height. The width of the rabbet 8 as illustrated 35 by the numeral 9 is of a width known in the trade as three point, or approximately five-sixteenths of an inch. By this construction, the lower portion of the furniture at 10 is wider than the upper portion 11.

In Figures 3 and 4 of the drawing it can be seen, that due to the furniture having a rabbet 8 on both longitudinal edges, one of the edges 10 impinge the type form, the upper portion of the furniture being of a reduced width due to the 45 rabbet 8, the portion 9 of the furniture forms a space or channel way 12 around the type form. During the printing operation, accumulated air and static pressure passes into these channel ways, thereby assisting in eliminating slurring and 50 wrinkling of paper being printed.

Interposed between the inner side edge of the chase 5 and my novel furniture 7 are quoins 13 and 14, each of which comprise two members 15, 16, 17 and 18. The members 15, 16, 17 and 18 55

are each provided with a rib 19 and a groove 20, the rib of each member engaging the groove of each member. The quoins 13 and 14 clamp the sides of the forms and hold them against transverse movement.

5 If desired, a bar 21 may be inserted at one end of the chase and quoins 22 and 23, identical in structure to quoins 13 and 14 may be interposed between the bar 21 and the furniture 7. The 10 quoins 22 and 23 in conjunction with the furniture, clamp the opposite ends of the form and hold it against transverse movement.

As illustrated in the transverse sectional view Figure 4 of the drawing, it can be seen that the 15 side wall 10 of the furniture being restricted as to height, the restricted portion grips the type form at its lowermost portion, thereby holding the form rigid, and thus preventing the type from working up, and further this restricted height of the side 20 wall eliminates the stripping of the form prior to the lock-up in the chase.

While the principles of the invention will always be adhered to, the invention is susceptible to certain changes and modifications and I do 25 not wish to limit myself to the exact structure and changes may be made without departing from the spirit or scope of the invention.

What I claim is:—

1. Furniture for printing comprising a bar, a 30 rabbet in each longitudinal side wall of said bar, the lower portion of said bar being of a greater width than the upper portion.

2. Printing furniture comprising a bar, a rabbet in each longitudinal side wall of said bar, 35 the lower portion of said bar being of greater width than the upper portion, said rabbet providing an offset in each longitudinal side wall of said bar.

3. Printing furniture comprising a bar, a rabbet in each longitudinal side wall of said bar, 40 the lower portion of said bar being of a greater

width than the upper portion, the lower edges of the side walls of the lower portion of said bar being uniplanar with the bottom face of said bar.

4. In combination, a chase, type forms surrounded by furniture in the chase, said furniture provided with a rabbet in each longitudinal side wall, the lower portion of said furniture being of a greater width than the upper portion and a channel way around said type forms.

5. In combination, a chase, type forms surrounded by furniture in the chase, said furniture provided with a rabbet in each longitudinal side wall, the lower portion of said furniture being of a greater width than the upper portion, the inner 10 side walls of the lower portion of said furniture 15 impinging the lower portions of said type forms and a channel way around said type forms.

6. In combination, a chase, type forms surrounded by furniture in the chase, said furniture provided with a rabbet in each longitudinal side 20 wall, the lower portion of said furniture being of a greater width than the upper portion, the inner side walls of the lower portion of said furniture impinging the lower portions of said type forms, a channel way around said type forms, said type 25 forms and furniture locked in said chase by quoins.

7. In combination, a chase, type forms surrounded by printing furniture, said furniture provided with a rabbet in each longitudinal side wall, 30 the lower portion of said furniture being of a greater width than the upper portion, the inner side walls of the lower portion of said furniture impinging the lower portions of said type forms, 35 the lower edges of the side walls of the lower portions of said furniture being uniplanar with the bottom faces of said furniture, a channel way around said type forms, said forms and furniture locked in said chase by quoins.

40 CHARLES RECKEWEG.
